UNITED STATES PATENT OFFICE

1,969,610

WINDOW FORMING MACHINE

Carl H. Jäger, Elberfeld, Germany

Application May 25, 1932, Serial No. 613,592

10 Claims. (Cl. 93—63)

This invention relates to new and useful improvements in machines for forming cut-outs in a continuous web passing through said machine, and for subsequently securing to said web in positions overlying said cut-outs, transparent or other sheet material in shapes and sizes corresponding more or less closely to cut-out apertures themselves.

A principal object of the invention is to provide a machine of the character set forth having novel means for forming an opening in a web.

A more specific object of the invention is to provide a machine of the type described having novel means for displacing the portion cut from the web, out of the plane of travel thereof.

Another object of the invention is to provide a machine of the stated character having novel means for removing the portion cut from the web from the machine.

20 Another object of the invention is to provide a machine as set forth having novel means for applying adhesive substances to the web adjacent the aperture cut therein.

Another object of the invention is to provide 25 a machine as set forth having a novel feed mechanism for accurately positioning and securing a covering of transparent material over the aperture formed in the web.

Another object of the invention is to provide 30 a machine of the stated character having novel means for severing predetermined lengths of a transparent web for the purpose of covering the opening formed in a second web.

A further object of the invention is to provide 35 a machine as set forth having a novel mechanism effecting the accurately timed occurrence of the various successive operations performed in the machine.

Other detail features and objects will be set 40 forth hereinafter and are disclosed in the accompanying drawings, in which

Figure 1 is a view in side elevation of the machine constituting my invention;

Figure 2 is a view in plan view of the 45 closure in Figure 1;

Figure 3 is a view in vertical section through the machine showing in addition the complete cam mechanism;

Figure 4 is a view in section on line 4—4 50 Figure 3; and

Figure 5 is a view on line 5—5 Figure 2.

Referring now more particularly to the drawings, a machine made in accordance with my invention comprises the vertical side supports 1 55 and 2 suitably spaced by the transverse bars 3.

In the present instance the continuous web 4 of paper, or like material, is carried longitudinally through the machine by the carrier rolls 5, 6 and 7 rigidly mounted respectively upon shafts 8, 9 and 10 which are rotatably journaled in 60 the side supports 1 and 2. The shaft 8 in the present instance extends outwardly beyond the side supports 1 and 2 and is provided with the gears 11 and 12 rigidly mounted at the extremities thereof. In a similar manner the 65 shafts 9 and 10 are provided with gears 13 and 14 mounted respectively at the extremities thereof adjacent the outer face of the side support 2. Rotation of the shaft 8 is effected preferably by means of a chain or belt 15 driven 70 by a sprocket wheel 16 arranged for rotation with the main shaft 17 of the machine and to which a source of rotative power is applied through the larger sprocket gear 18. The chain passes from the wheel 16 about a similar wheel 75 19 rigidly mounted upon a transverse stub shaft 20 rotatably journaled in the side support 1. A gear 21 is mounted on the shaft 20 adjacent the wheel 19 and arranged for rotation therewith. The gear 21 is meshed with a similar 80 gear 22 rigidly mounted on a shaft 23 rotatably mounted in bearings in the aforementioned side supports 1 and 2 respectively. The aforesaid gear 11 in meshing with the gear 22 completes the driving connection between the shaft 8 85 and the drive or main shaft 17 effecting rotation of the said shaft 8. Rotation of the shaft 9 is effected by the gear 12 at the opposite end of the shaft 8 which meshes with an idler gear 24 in turn meshing with the gear 13 on the said 90 shaft 9. The spindle 25 on which the idler gear 24 is mounted is provided, in the present instance, with a sprocket wheel 26 having a chain 27 thereabout subsequently passing about a wheel 28 rigidly mounted on the shaft 10 having the web carrier roll 7 mounted thereon. Tension on the chain 27 is, in the present instance, adjusted by selectively positioning the small sprocket wheel 29 rotatably mounted on the outwardly extending stub shaft 30.

It should be noted that the gears and spindles imparting rotation to the web carrier rolls 5, 6 and 7 respectively as described above are of the same diameter and effect proper timing for the advancement of the web 4 through the 105 machine.

A gear 31 of substantially the same diameter as the gears mentioned above is meshed with the gear 11 and rigidly mounted on a shaft 32 rotatably journaled in the supports 1 and 2. 110

Suitably positioned upon the shaft 32 are the cylindrical segmental cutter supports 33, 33 respectively supporting in each instance a segmental cutter 34 disposed parallel with respect to the longitudinal axis of the machine and arranged for cutting contact with the web 4 against the peripheral surface of the carrier roll 5, the said cutters 34 each effecting a longitudinal cut in the web 4.

10 A longitudinally positioned rectangular or other suitably shaped segmental cutting edge 35 is mounted upon a segmental section 36 removably mounted on the shaft 23, the rotation of the said shaft 23 being suitably timed and the cutter 35 being so positioned that as the web 4 advances through the machine the said cutter 35 will further contact with the web against the roll 5 coinciding with the previous cuts produced by the cutters 34 as described supra, completing the cutting of a blank from the center of the web.

For the purpose of displacing the blank from the web 4 and leaving an aperture 37 therein, I provide a plunger 38 extending diametrically through the shaft 23 as shown in Fig. 3 of the drawings and which upon completion of the cutting operation is actuated by the finger 39 against the action of a spring 40 to displace the blank from the plane of travel of the web 4.

30 In the present instance I mount the finger 39 rigidly upon a shaft 41 which is rocked by the cam roller 42 acting through the rocker arm 43 against the spring 44, the said cam roller 42 contacting with the peripheral face of the cam disk 45 rigidly mounted and rotatable with the shaft 23.

For the purpose of carrying the blank cut from the web 4 outwardly of the machine, I provide a pair of arcuately shaped fingers 46, 46 mounted upon a rod 47, and arranged to conform approximately to the surface contour of the web carrier roll 5, the said rod 47 being supported and movable about the shaft 8 by means of the rotatable collars 48 having the arms 49 rigidly supporting the said rod 47. Rotatably mounted upon the rod 47 and connected to the fingers 46 by means of a sleeve is a downwardly extending arcuate arm 50 passing about the lower surface of the roll 5, and held in spaced relation therefrom by means of a spring 51 secured intermediate the said arm 50 and a depending arm 52 rigidly secured upon the aforementioned rod 47.

With the arm 50 held in spaced relation from the roll 5 by the said spring 51, the extremities of the fingers 46 grip the blank cut from the web 4 against the said roll 5 and the rotation of the roll 5 in conjunction with the clockwise movement of the rod 47 and fingers 46 about 60 the shaft 8 carries the blank away from said web to a point below the said roll 5. The rod 47 supporting the fingers 46 is moved clockwise of the roll 5 by means of the cam roller 52 riding on the surface contour of the cam disk 53 and 65 operating through the link train 54 connected to said rod 47 against the spring 54a. When the fingers 45 have moved the portion cut from the web 4 a predetermined distance clockwise about the roll 5, the blank is released from 70 the grip of the fingers 46 by rocking the arm 50, rigidly connected to said fingers, about the rod 47. The arm 50 and fingers 46 are rocked about the rod 47 by means of a cam roller 55 normally engaging the under surface of the arm 75 50, lifting of the said cam roller 55 being ac-

complished through the levers 56 connected at one end thereto and at the other end to a second cam roller 57 riding on the peripheral surface of the cam disk 58 and acting against a spring 58a.

In the present instance the cutting of the blank of material from the web 4 and the displacing thereof from the plane of travel of said web by the plunger 38 are so timed in conjunction with the cam disks 53 and 58 that the gripping of the blank by the fingers 46 takes place simultaneously with the depressing of said blank below the web 4, the carrying of the cut out portion about the roll 5 and the subsequent releasing thereof by tripping the fingers 46 taking place successively after said fingers have gripped the blank. With the release of the material cut from the web 4 by the tripping of the fingers 46 through the rocking of the arm 50, the material is carried by a chute 59 outwardly of the machine.

A plurality of idler rollers 60 are rotatably mounted upon a rod 61 and abet the movement of the blank cut from the web 4 about the roll 5, the pressure of the rollers 60 against the roll 5 being effected by means of a spring 62 acting through the rocker arm 63 which is pivoted about a rod 64 disposed transversely of the machine.

Adhesive material is deposited on the web 4 adjacent the edges of the opening 37 formed therein as described above, during the travel of the said opening 37 over the carrier roll 6. In the present instance I accomplish the depositing of said adhesive substances on the web by rigidly mounting a roller 65 on the shaft 66 arranged for rotation by means of a gear 67 mounted at one extremity thereof and meshed with the aforementioned gear 21. The roll 65 is equipped with a removable segment 68, having a raised welt 69 thereon arranged for contact with the web 4 adjacent the edges of the aperture 37 therein. The adhesive material is placed upon the raised welt 69 of the segment 68 by previous contact with a roller 70 having a coating of adhesive thereon by reason of the contact of said roller 70 with the roller 71 which in turn contacts with the roller 72 residing in part in the tray 73 containing the said adhesive material. The tray 73 is removably mounted on the machine and the rollers applying the adhesive material to the application roll 65 are driven by a suitable gear mechanism meshing with a gear mounted on and arranged for rotation with the aforementioned shaft 66.

In the present instance I prefer to mount the "cellophane", or other transparent material, feed mechanisms upon the removable supports 74 which are adjustably mounted upon the side supports 1 and 2 by means of a toothed gear 75 and rack 76 formed on one under face of the supports 74.

A "cellophane" or other transparent web 77 is fed from a spool 78 about a roller 79 rotatably mounted upon a shaft 80 and subsequently passes over a rotatable roller 81 supported on the pivotally mounted arm 82, provided at its outer extremity with a spring 83, affording a means of tensioning the said web during the feeding thereof. The web 77 is then fed below a roller 84, rigidly mounted upon the rotatable shaft 85 and about a similar roller 86 similarly mounted upon a shaft 87. At this point the tension of the web 77 is maintained by a roller 88, rotatably mounted upon a spindle 89 sup-

ported in one arm 90 of a rocker lever 91 pivotally mounted about the shaft 92, the other arm 93 of the said rocker lever 91 being attached to the side wall of the machine by a spring 94 connected intermediate the said arm and the side wall, thus insuring sufficient contact of the roller 88 with the web 77 against the roller 88. The web 77 then passes obliquely downwardly intermediate a roller 95 mounted on the shaft 96 and a roller 97 having diametrically opposed blade or cutter elements 98 disposed obliquely in the peripheral surface thereof with respect to the longitudinal axis of the said roller. The cutter elements 98 on the roller 97 operate to cut predetermined lengths of material from the transparent web 77 against the roller 95 over which the web 77 passes.

The roller 95 and shaft 96 are rotated by a chain 99 which passes from a wheel 100 on the main shaft 17 of the machine about the wheel 101 mounted at one extremity of the shaft 98, the said chain in a similar manner passing about the wheels 102 and 103 respectively mounted upon the shafts 104 and 105. A gear 103^a is mounted at the end of the shaft 105 adjacent the support 2 and arranged for rotation therewith, the said gear 103^a meshing with gear 14 mounted on the shaft 10. The arrangement described above tends to act as a balancer or connection intermediate the mechanism driven by the chain 15 and that driven by the chain 99 to more efficiently time the operation of the machine.

The severed section of transparent material is projected downwardly of the machine to a platen 106, and is maintained in flat relation thereon by the spaced rods 107. The section of the transparent material is then positioned upon the web 4 which is held in contact with the roller 7 by the idler rollers 108 rotatably mounted upon the shaft 109 supported intermediate the rocker arms 110, 110 pivotally mounted on a rod 111, the said arms 110, 110 secured at their opposite ends to a transverse support 112^a on the machine by a spring member 112, the said spring acting through the rocker arms 110 to effect a contact of sufficient pressure of the idler rollers 108 on the web 4 carried by the roller 7. The length of the material which is severed from the continuous web 77 and placed in overlying relation with the opening 37 in the web 4 is adhered thereto by the adhesive material deposited adjacent the edges of the opening by the segmental rectangular section 69, sufficient pressure being applied to the severed section of the web 77 overlying the openings 37 in the web 4 by the roller 113 to press the said transparent section into contact with the web 4 during passage beneath the roller 113 which is rotatably mounted on a shaft 114 supported in one arm of the rocker arm 115. The other branch of the arms 115 is connected by means of a rod 116 to a lever 117 pivotally mounted about the rod 118 having a cam roller 119 rotatably mounted thereon and arranged for rolling contact with the peripheral contour of a cam disk 120 rigidly mounted upon the main shaft 17 of the machine, the said lever 117, in the present instance, being actuated against the action of a spring 121 secured intermediate the outer extremity of said lever 117 and a rod 122 projecting inwardly of the side wall 2 of the machine.

It should be noted that the roller 113 pressing against the transparent section disposed over the opening 37 in the web 4 is formed in a plu-

rality of sections, spaced longitudinally for the purpose of permitting the contact of the said roller with the transparent material about the rods 107 which overlie the platen 106 for the purpose of maintaining the transparent section in place thereon.

In the present instance to effect the accurate cutting of the webs 4 and 77 respectively, I provide the shafts 32 and 23, having the cutting tools mounted thereon, with novel means for regulation of the contact pressure of the said tools with the cutting surfaces. The above mentioned regulation of the cutting pressure, I prefer to accomplish by means of springs 123 residing in the slots 124 formed in the side supports of the machine as shown, the tension in the springs 123 being afforded very sensitive adjustment by means of the three hand nuts 125, 126 and 127 respectively positioned in screwed relation upon the screw 128 contacting with the outer end of the springs 123.

It should be further noted that the travel of the web 4 through the machine and the feeding of the transparent web 77 are suitably timed in conjunction with the operations performed during travel of said webs as to produce finished product which is a substantial improvement over products of similar character produced heretofore, the feed rolls for said web 77 being driven by suitable gear trains connected in any suitable manner to the main drive system of the machine.

While I have disclosed the detail construction of my invention, I do not wish to be limited thereto except as recited in the appended claims.

I claim:

1. In a machine, the combination with means for cutting openings in a traveling web at intervals along the course thereof corresponding to the contour of a window opening, a cam-operated plunger associated with said cutting means displacing the blank, defined by the cutting means, out of the plane of travel of the web, and means at the opposite side of said web from the displacing means and intermittently movable toward and away from the web in timed relation with said displacing means for gripping the blank and carrying said blank outwardly of the machine.

2. In a machine, the combination with means for cutting openings in a traveling web at intervals along the course thereof corresponding to the contour of a window opening, means associated with said cutting means displacing the blank, defined by the cutting means, out of the plane of travel of the web, and pivotally mounted arcuate means reciprocable toward and away from said web in timed relation with said displacing means for gripping the blank and carrying said blank outwardly of the machine.

3. In a machine, the combination with means for cutting openings in a traveling web at intervals along the course thereof corresponding to the contour of a window opening, means associated with said cutting means displacing the blank, defined by the cutting means, out of the plane of travel of the web, and reciprocating fingers operating in timed relation with said displacing means for gripping the blank carrying the same outwardly of the machine and subsequently releasing said blank.

4. In a machine, the combination with means for cutting openings in a traveling web at intervals along the course thereof corresponding to the contour of a window opening, means as-

- sociated with said cutting means displacing the blank, defined by the cutting means, out of the plane of travel of said web, means intermittently movable toward and away from the web in timed relation with said displacing means for gripping the blank and carrying the blank outwardly of the machine, means depositing adhesive material on the web adjacent the contour of the opening, and timed means positioning a length of transparent material on the web overlying said opening and pressing said material to adhere to said web. 5. In a machine, the combination with means for cutting openings in a traveling web at intervals along the course thereof corresponding to the contour of a window opening, means associated with said cutting means displacing the blank, defined by the cutting means, out of the plane of travel of the web, pivoted means reciprocable toward and away from said web in timed relation with said displacing means for gripping the blank and carrying said blank outwardly of the machine, means depositing adhesive material on the web adjacent the contour of the opening, and means positioning a length of transparent material on the web overlying said opening and pressing said material to adhere to said web, said latter two means acting in timed relation with said cutting and removing means. 6. In a machine, the combination with means for cutting openings in a traveling web at intervals along the course thereof corresponding to the contour of a window opening, means associated with said cutting means displacing the blank, defined by the cutting means, out of the plane of travel of the web, pivoted means reciprocable toward and away from said web in timed relation with said displacing means for carrying the blank outwardly of the machine and subsequently releasing said blank, means depositing adhesive material on the web adjacent the contour of the opening, and means positioning a length of transparent material on the web overlying said opening and pressing said material to adhere to said web, said latter two means acting in timed relation with said cutting and removing means. 7. In a machine, the combination with means for cutting openings in a traveling web at in-
- tervals along the course thereof corresponding to the contour of a window opening, means associated with said cutting means displacing the blank, defined by the cutting means, out of the plane of travel of said web, pivoted means reciprocable toward and away from the web in timed relation with said displacing means for gripping the blank and carrying the blank outwardly of the machine, means operative to pivot said fingers and release said blank means depositing adhesive material on the web adjacent the contour of the opening, and means positioning a length of transparent material on the web overlying said opening and pressing said material to adhere to said web, said latter two means acting in timed relation with said cutting and removing means. 8. In a machine, the combination with a pair of opposed cylindrical rolls, of means mounted on one of said rolls for cutting apertures at intervals along the course of a web traveling between said rolls, means associated with said cutting means for displacing the blank defined thereby out of the plane of travel of the web, and means movable circumferentially of the other roll to grip the blank cut from the web and carry the same outwardly of the machine. 9. In a machine, the combination with a pair of opposed cylindrical rolls, of means mounted on one of said rolls for cutting apertures at intervals along the course of a web traveling between said rolls, means associated with said cutting means for displacing the blank defined thereby out of the plane of travel of the web, and fingers movable circumferentially of the other roll to grip the blank cut from the web and carry the same outwardly of the machine. 10. In a machine, the combination with a pair of opposed cylindrical rolls, of means mounted on one of said rolls for cutting apertures at intervals along the course of a web traveling between said rolls, means associated with said cutting means for displacing the blank defined thereby out of the plane of travel of the web, and pivotally mounted means movable circumferentially of the other roll to grip the blank cut from the web and carry the same outwardly of the machine.
